UNITED STATES PATENT OFFICE.

NELLIE KINSELLA PETERSON, OF BISBEE, ARIZONA.

SKEIN-HOLDER.

1,218,457.

Specification of Letters Patent.

Patented Mar. 6, 1917.

Application filed March 3, 1916. Serial No. 81,960.

To all whom it may concern:

Be it known that I, Mrs. NELLIE KINSELLA PETERSON, a citizen of the United States, residing at Bisbee, in the county of Cochise 5 and State of Arizona, have invented new and useful Improvements in Skein-Holders, of which the following is a specification.

This invention relates to improvements in skein holders and has particular application 10 to a device for holding a number of skeins of silk, mercerized cotton or the like.

In carrying out the present invention, it is my purpose to provide a skein holder for holding a plurality of skeins of silk, mercerized cotton or the like and whereby the skeins will be held in such manner that the strands or threads, may be removed therefrom and conveniently applied thereto in a like manner.

20 It is also my purpose to provide a skein holder which will embrace the desired features of simplicity, efficiency and durability, which may be manufactured and marketed at small cost and which may be conveniently 25 carried about and handled.

With the above and other objects in view, the invention consists in the construction, combination and arrangement of parts hereinafter set forth in and falling within the 30 scope of the claims.

In the accompanying drawing:

Figure 1 is a perspective view of a skein holder constructed in accordance with the present invention.

35 Fig. 2 is an end view thereof.

Fig. 3 is a cross sectional view thereof.

Referring now to the drawing in detail, 1 designates a bar of suitable length and 40 angular in cross section. In the present instance, I have shown the bar as square in cross section and fastened to one end of the bar is a plate 2 of a shape corresponding to the cross sectional configuration of the bar 45 and having the edges thereof formed with upturned and inturned fingers 3 respectively. Fastened to each side of the bar adjacent to the other end thereof is a gripping plate 4 bent upon itself between its ends and

having one member fastened to the bar and 50 the other member overlying the first member and coöperating therewith to grip the skein of silk.

In practice, the skein of silk is opened and 55 cut into substantially equal lengths and these lengths are then doubled upon themselves and again double and the loop formed in the second folding of the silk is slipped under the fingers 3 and the end portions of the silk slipped between the members of the 60 gripping plate 4. Thus, the gripping plate and the corresponding finger 3 coact to hold the skein in proper position upon the particular side of the bar 1. In a similar manner the other skeins are secured to the remaining sides of the bar until the bar is filled to its capacity. 5 designates a sleeve 65 composed of any suitable material, preferably of a flexible nature, adapted to fit over the bar 1 and inclose the skeins of silk thereon so as to protect the silk from dust, dirt and other foreign matter.

While I have herein shown and described one preferred form of my invention by way of illustration, I wish it to be understood 75 that I do not limit or confine myself to the precise details of construction herein described and delineated, as modification and variation may be made within the scope of the claims and without departing from the 80 spirit of the invention.

I claim:

1. A skein holder comprising a bar having a number of sides, holding devices on the respective sides of said bar adjacent to 85 one end thereof, and a holding device on the other end of said bar common to all of said first holding devices and coöperating therewith to hold skeins of silk on the respective sides of the bar.

2. A skein holder comprising a bar having a number of sides, a plate at one end of the bar conforming to the cross sectional shape of the bar, fingers on the respective edges of said plate, and gripping plates on 95 the respective sides of the bar adjacent to the other end thereof coöperating with said fingers to hold skeins of silk on the bar.

3. A skein holder comprising a bar having a number of sides, a plate at one end of the bar conforming to the cross sectional shape of the bar, fingers on the respective edges of said plate, gripping plates on the respective sides of the bar adjacent to the other end thereof coöperating with said fingers to hold skeins of silk on the bar, and a

sleeve for inclosing the bar and the skeins of silk thereon.

10

In testimony whereof I affix my signature in presence of two witnesses.

Mrs. NELLIE KINSELLA PETERSON.

Witnesses:

A. J. PETERSON,

Mrs. A. ELBHITE.
